Primary Examiner — Shannon W Morgan*Assistant Examiner* — Altaira J Swangin(74) *Attorney, Agent, or Firm* — WPAT, P.C., Intellectual Property Attorneys; Anthony King(57) **CLAIM**

The ornamental design for a vehicle hood louver assembly, as shown and described.

DESCRIPTION

FIG. 1 is a back perspective view of the vehicle hood louver assembly;

FIG. 2 is a back perspective view thereof;

FIG. 3 is a front perspective view thereof;

FIG. 4 is a right side view thereof, the left side view being a mirror image thereof;

FIG. 5 is top perspective view thereof; and,

FIG. 6 is a bottom perspective view of the vehicle hood louver assembly showing my new design.

The broken lines shown around the perimeter of the vehicle hood louver assembly depict boundaries which form no part of the claimed design. The dashed lines, showing the body of the vehicle hood louver assembly broken away in FIGS. 1-4, indicate a boundary which forms no part of the claimed design, and shows that the appearance of any portion of the article between these break lines forms no part of the claimed design.
